UNITED STATES PATENT OFFICE

2,482,679

AIR CLEANER

Alexander J. McAllister and John J. Dreznes,
Chicago, Ill., assignors to United Specialties
Company, Chicago, Ill., a corporation of Dela-
ware

Application June 20, 1947, Serial No. 755,968

2 Claims. (Cl. 183—47)

1

This invention relates to an air cleaner and has for one object to provide a cleaner which may be arranged or adjusted for washing after use without separating any of the parts and without disassembling the cleaner.

Another object is to provide an air cleaner including a mass of curled hair or equivalent material as a filtering medium, and to provide means for compressing said material for use and for readily decompressing it for washing without disassembly of the cleaner or removal of any of its parts.

Other objects will appear from time to time in the specification and claims.

The invention is illustrated more or less diagrammatically in the accompanying drawings, wherein:

Figure 1 is a top plan view;

Figure 2 is a transverse section taken at lines 2—2 of Figure 1;

Figure 3 is a bottom plan view.

Like parts are indicated by like characters in the specification and drawings.

The cleaner comprises a housing member 1 which is provided with a bottom which may be inclined as shown. An offset outlet opening is provided at 2, and this member is conveniently made in tubular form as shown. A slotted sleeve 3 is fixed to the tubular portion 2 by welding or otherwise, and a clamping member is positioned about the slotted portion of the sleeve 3. This clamping member is indicated at 4 in Figures 2 and 3. A set screw 5 is used to tighten the clamping member.

The housing includes a generally cylindrical portion 6 which may be integral with the bottom. The portion 6 is outwardly turned at 7 and inwardly turned at 8. Between the parts 7 and 8 is engaged a top or cover member 9. This member is provided with a plurality of perforations 10.

Within the housing 1 and bounded by the portion 6 is a quantity of curled hair 11. Curled hair or mechanically equivalent material is to be understood where the expression "curled hair" is used, and the invention is not strictly limited to the use of curled animal hair. A mixture of materials, or any material generally the equivalent mechanically of curled hair, may be used.

A perforated pressure plate 12 is provided within the housing 1, 6. This plate may carry a peripheral flange 13. A depression 14 is preferably formed in it, and one or more stiffening grooves 15 may be formed in the plate 12 if desired.

A compression screw 16 is seated for rotation in

5 a nut or other threaded member 17 which is secured in relation to the bottom of the housing 1. The head 18 of the screw extends outside of the housing for convenient use. The screw, if desired, may be enlarged at the opposite end at 19. The end of the screw, whether enlarged or not, contacts the portion 14 of the pressure plate 12. By adjustment of the screw 16, the degree of compression upon the curled hair or other material which is positioned between the top plate 9 and the pressure plate 12 may be varied for adjustment, or the pressure may be released or substantially reduced for washing.

Although we have shown an operative form of 15 our invention, it will be recognized that many changes in the form, shape and arrangement of parts can be made without departing from the spirit of the invention, and our showing is therefore to be taken as, in a sense, diagrammatic.

20 The use and operation of this invention are as follows:

The device of the present invention is associated with means for using or otherwise dealing with air. One such means is an internal combustion engine. Ordinarily the cleaner is positioned to receive air through the plate 9 and to discharge it through the member 2 and the slotted sleeve 3. It may be positioned on the upstream side of a carburetor.

30 However the device is used or connected, it may be positioned in any position. The plate 9, which has been referred to as a top plate, need not be positioned to face upwardly. When the device is used, air is drawn through the perforations 10 and the plate 9, through the mass of curled hair 11 or equivalent material, and passes beyond the plate 12 to be discharged through the members 2 and 3. As the air passes through the filter mass, solid material is caught by the filtered mass, and the cleaned air passes from the cleaner.

40 In the course of time, and after considerable use, the filter mass 11 will have picked up a substantial quantity of foreign matter such as dust and other solid material which was present in the air as it entered the cleaner. It is important to be able to remove this material easily. It is done in the following manner: The screw 16 is backed off and the pressure on the filter mass is reduced. Curled hair or equivalent material is springy, and when the compression upon the filter mass is reduced, it expands substantially. It will expand as the screw is backed away, and in its expansion it will force the pressure plate 12 away from the plate 9. When substantial expan-

sion of the filter mass has occurred, it becomes easy to wash this mass. Water or other cleaning material is discharged through the cleaner, and the foreign material in the filter mass is washed outwardly with the cleaning fluid, and the foreign material is carried away from the filter body. The filter is thus clean and ready for re-use. To prepare it for re-use, the screw 16 is rotated to force the pressure plate 12 against the filter mass 11 and to return that mass to the desired degree of compression, whereupon the cleaner is again ready for use.

The device thus comprises an efficient dry air filter and assembly and provides within itself means for adjustment which permits effective cleaning by water, air or other fluid without the removal of any part from the cleaner and without any adjustment except that which reduces the pressure on the filter mass and permits it to expand sufficiently so that effective washing or renovation of the filter mass can be accomplished.

We claim:

1. In combination, in an air cleaner, a housing, an inlet member permanently fixed in said housing, said member formed to provide inlet openings, an outlet passage from said housing, a filter mass of curled hair positioned within said housing and in contact with said inlet member, and an air-pervious pressure member positioned permanently within said housing, said pressure member being in contact with said filter mass and effective to hold it in place, an adjustable means for forcing said pressure member against said filter mass to compress the same, 35 said adjustable means being also effective to free

said pressure member for movement, away from said inlet member.

2. In combination, in an air cleaner, a housing, an inlet member fixed in said housing, said member formed to provide inlet openings, said housing being permanently crimped over said inlet member and securing it in permanent position, an outlet passage from said housing, a filter mass positioned within said housing in the line of air entering said inlet member and in contact with said inlet member, and an air-pervious pressure member positioned within said housing in the line of air passing through said cleaner, said pressure member being in contact with said filter mass and effective to hold it in place, an adjustable means for forcing said pressure member against said filter mass to compress the same, said adjustable means being also effective to free said pressure member for movement.
